UNITED STATES PATENT AND TRADEMARK OFFICE
CERTIFICATE OF CORRECTION

PATENT NO. : D618,821 S
APPLICATION NO. : 29/341082
DATED : June 29, 2010
INVENTOR(S) : Kristian Larsen

Page 1 of 1

It is certified that error appears in the above-identified patent and that said Letters Patent is hereby corrected as shown below:

Title page 1, item 73, the country code in the Assignee address should be "DK" not "DE"

Title page 1, the Locarno class should be "Locarno Class 09-03", not "Locarno class 24-01"

Signed and Sealed this
Tenth Day of July, 2012

David J. Kappos
Director of the United States Patent and Trademark Office
